(57) **CLAIM**

The ornamental design for a modular merchandiser, as shown and described.

DESCRIPTION

FIG. 1 is a perspective view of a modular merchandiser, showing our new design.

FIG. 2 is a front elevational view thereof.

FIG. 3 is a top plan view thereof.

FIG. 4 is a side elevational view thereof, the other side being a mirror image; and,

FIG. 5 is a rear elevational view thereof.

The surface(s) of portion(s) of the article not shown in the drawing or described in the specification form(s) no part of the claimed design.
